(57) **CLAIM**

The ornamental design for an tire for automobile, as shown and described.

DESCRIPTION

FIG. 1 is a perspective view of an tire for automobile showing the new design;

FIG. 2 is a front view of the tire for automobile shown in FIG. 1, it being understood that the pattern repeats uniformly throughout the circumference of the tire;

FIG. 3 is a rear view of the tire for automobile shown in FIG. 1;

FIG. 4 is a left side view of the tire for automobile shown in FIG. 1, which is the same as the right side view thereof;

FIG. 5 is an enlarged view showing a portion of the tire for automobile shown in FIG. 2; and,

FIG. 6 is a further enlarged view showing a portion of the tire for automobile shown in FIG. 5.
